CORNER INSERT FOR CEILING TRACKS

Melvin W. Tompkins and George F. Retz, New Castle,
Ind., assignors to American Standard Inc., New York,
N.Y.

Filed May 11, 1971, Ser. No. 142,426

Term of patent 14 years

Int. Cl. D8—09

U.S. Cl. D8—225

FIG-1

FIG-2

FIG-3

FIG-4

FIG-5

FIG-6

FIG-7

FIG-8

FIG-9

FIG-10

FIG. 1 is a top and rear perspective view of a corner insert for ceiling tracks showing our new design;

FIG. 2 is a bottom and front perspective view thereof;

FIG. 3 is a top plan view thereof;

FIG. 4 is a front side elevational view thereof;

FIG. 5 is a rear side elevational view thereof;

FIG. 6 is a top and rear perspective view of another embodiment of our new design wherein the corner is formed by an acute angle rather than square;

FIG. 7 is a bottom and front perspective view of FIG. 6;

FIG. 8 is a top plan view of FIG. 6;

FIG. 9 is a front side elevational view of FIG. 6;

FIG. 10 is a rear side elevational view of FIG. 6.

We claim:

The ornamental design of a corner insert for ceiling tracks, substantially as shown.
